CLAIM

The ornamental design for a case for spectacles or other articles, as shown and described.

DESCRIPTION

FIG. 1 is a perspective view of the case for spectacles or other articles;

FIG. 2 is a side view, with the opposite side being a mirror image thereof;

FIG. 3 is a front view, with the rear view being a mirror image thereof;

FIG. 4 is a top plan view thereof;

FIG. 5 is a bottom view thereof;

FIG. 6 is a perspective view, with the top shown in an open position; and,

FIG. 7 is a perspective view, shown in use.

The broken line showing of a strap in the drawings is for illustrative purposes only and forms no part of the claimed design.
